DESIGN FOR A STRUCTURAL TOY ELEMENT

Alfred C. Gilbert, Hamden, Conn., assignor to
The A. C. Gilbert Company, New Haven, Conn.,
a corporation of Maryland

Application April 29, 1937, Serial No. 69,051

Term of patent 14 years

To all whom it may concern:

Be it known that I, Alfred C. Gilbert, a citizen of the United States, residing at Hamden, in the county of New Haven and State of Connecticut, have invented a new, original, and ornamental Design for a Structural Toy Element, of which the following is a specification, reference being had to the accompanying drawing, forming part thereof.

Figure 1 is a view of either side, Figure 2 is an edgewise view looking from the left at Figure 1, Figure 3 is an edgewise view looking at Figure 1 in the direction of arrow 3, and Figure 4 is a perspective view, of a structural toy element showing my new design.

The present design comprises as principal and dominating features thereof, cylindrical bodies of like size and shape forming portions of a structural toy element projecting outwardly from a

centrally disposed disc-like body of thickness approximately equal to the diameter of said cylindrical bodies, two of said cylindrical bodies being longitudinally aligned in axial relation to said disc-like body and separated by the thickness thereof, and others of said cylindrical bodies being ordered in radial positions about the peripheral face of said disc-like body with their root ends substantially touching one another at said face and concealing substantially all parts of said face other than fragments thereof having a generally triangular shape bounded by the said root ends of the cylindrical bodies and by the axial extremities of said peripheral face.

I claim:

The ornamental design for a structural toy element substantially as shown and described.

ALFRED C. GILBERT.
